UNITED STATES PATENT OFFICE.

GEORGE C. FARKELL, OF ELYRIA, OHIO.

MANIPULATOR.

1,152,014.

Specification of Letters Patent. Patented Aug. 31, 1915.

Application filed February 24, 1915. Serial No. 10,253.

To all whom it may concern:

Be it known that I, GEORGE C. FARKELL, a citizen of the United States, and resident of Elyria, in the county of Lorain and State 5 of Ohio, have invented certain new and useful Improvements in Manipulators, of which the following is a specification.

My invention relates to the art of rolling, and, while not restricted to such use, has 10 particular reference to a novel manipulator used in handling rolled metal shapes.

An object in the design of the present device is to provide means for mechanically manipulating the shape or ingot in the interval between its travel through the various passes of a rolling mill. Heretofore, in many instances, this work has been performed by manual labor. As will be understood, this labor was extremely arduous, due 20 to the weight of the work and the attendant high temperature.

One of the particular objects in the construction of the present device is to provide for a motion approximating closely the motion attained by manually manipulating the work, to the end that the work is not bodily lifted to any appreciable extent, thus economizing in the power required for the operation of the manipulator. A further advantage in thus minimizing the extent of movement of the work is in the economy of time required for the turning act. The results desired are accomplished in the present mechanism by very simple expedients. 30 The mechanism will be more fully understood by reference to the accompanying drawings, wherein:

Figure 1 is a side elevation of a device constructed in accordance with my invention, Fig. 2 is a plan view thereof, Fig. 3 is an end view of the device, Fig. 4 is a front elevation of the construction shown in Fig. 7, Fig. 5 is a diagrammatic illustration of the location of the manipulator with relation to the roller feed table of the rolling mill, Fig. 6 is a diagrammatic illustration of the path followed by the work in being turned, Fig. 7 is a side elevation of a slightly modified construction, and Fig. 8 is a plan view thereof.

Referring more particularly to the drawings, it will be seen that on a support, or pier 10, I superpose standards 11 between which is mounted a fluid pressure cylinder 55 12 having a piston and a piston rod 13.

Brackets 14 on the cylinder serve to support one end of tracks 15. The opposite ends of the tracks are supported on a hydraulic piston 16 coöperating with a cylinder 17, which rests upon an abutment 18. Connected to the forward end of the piston rod 13 is a carriage 19 adapted for horizontal reciprocation upon the track 15. It will be seen by the arrangement described that the carriage is adapted for vertical and horizontal movement, due to the action of the fluid pressure means described.

Mounted upon the carriage 19 are supports 20, between which a fluid pressure cylinder 21 is rotatably mounted. Within the cylinder is mounted a piston having a piston rod 22, the forward end of which engages a toothed segment 23 pivoted at 24 in a pair of frame members 25, which frame members are pivoted coincidently with the cylinder 21 at the point 26. While the frame member and piston are pivoted at the same point, they are adapted for relative movement on their pivots. Engaging the toothed portion of the segment 23 is an idler 27, which, in turn, engages a toothed segment 28 carrying on one face thereof a wrench, or work manipulating member consisting of upper and lower arms 29, 30. The segment 28 is pivoted at 31 in the frame members 25. The idler 27 is mounted on a shaft, and secured to the shaft is a crank 32 which is connected to a link 33, the lower end of which has a fixed pivot 34 on the carriage 19.

The apparatus just described forming my improved manipulator, is positioned between adjacent rollers of a feed table formed by the series of feed rollers 36 at a suitable distance from the reducing rolls of a rolling mill 35, as is shown in Fig. 5. The feed 95 rollers 36 are shown in elevation relative to the manipulator in Figs. 1 and 7.

The operation of the device just described is as follows: While the work is leaving the rolls 35, shown in Fig. 5, the manipulator, which is then located in a position beneath the plane of the top of the feed table, formed by the feed rollers 36, is raised by the fluid pressure piston 16 to the proper height. As the work leaves the reducing rolls of the rolling mill 35 the wrench is positioned properly by admitting fluid pressure to the cylinder 12. Thereafter fluid pressure is admitted to the cylinder 21 and the wrench is rotated on its axis 31 and coincidentally 105 110 115

is lowered bodily, by reason of the crank and link 32, 33, with the result that the center 37 of the work, as shown in Fig. 6, follows a line corresponding substantially to the full line 38 shown in that figure. The path of turning movement of the center 37 of the work (shown in Fig. 6 by the full line 38), closely approximates the path of turning movement of the center 37 when the work is turned manually on the feed rollers 36 (a path corresponding to the line 39 of Fig. 6.) After moving the work to the position shown in dotted lines in Fig. 6, the carriage is actuated to move the wrench away from the work, whereupon the wrench is rotated to its original position and lowered out of the plane of the table.

In the construction shown in Figs. 7 and 8 the elements correspond with those heretofore described, with the exception that the wrench rotating cylinder 40 is pivoted to the carriage at 41 and is rigid with a frame 42. The piston rod 43 terminates in a rack 44 having a guide slot 45 therein with which rollers 46 coöperate, such rollers being fixed on the frame 42. The cam slot 47 is provided in the rack 44 with which slot a roller 48, mounted on standards 49 carried by the carriage 50 coöperates. Rigid with the frame 42 are standards 51, between which the toothed member 52 is pivoted at 53. Inasmuch as the standards 51 have a vertical movement with relation to the standards 49 and roller 48, I have provided a slot 54 in the standards, which slot registers with the roller 48. The operation is substantially identical with that described in connection with the apparatus shown in Figs. 1 and 2, the movement of the work being the same in each instance. It will be understood, of course, that on a return movement of the rack bar 44 the toothed member 52 and the wrench are rotated and simultaneously lowered. This is an illustration of only one of the modifications which might be made in the apparatus described, and such modifications as are within the scope of my claims I consider within the spirit of my invention.

I claim:

1. In a manipulator, the combination with a feed table of a carriage, means for moving the same into and out of the plane of the work to be manipulated, a wrench member for turning the work, means for rotating the wrench member, and means for bodily moving said wrench member into different horizontal planes simultaneously with its rotating movement, substantially as described.

2. In a manipulator, the combination with a feed cable of a wrench member, means for positioning said member in proper relation to the work to be manipulated, means for rotating said wrench member and there-by elevating the work, and means for bodily

lowering said wrench member simultaneously with its rotary movement, substantially as described.

3. In a manipulator, the combination with a feed table of a carriage, means for horizontally moving said carriage, a motor on said carriage, a work manipulating member rotatably mounted on said carriage and actuatable by said motor, and means for bodily lowering said member during its turning movement, substantially as described. 75

4. In a manipulator, the combination with a feed table of a support, a work manipulating member mounted on said support, means for rotating said manipulating member, and means for bodily lowering and raising said work manipulating member, the lowering movement occasioned by said last named means occurring simultaneously with the turning movement of said rotary member, substantially as described. 80

5. In a manipulator, the combination with a feed table of a support, means for moving said support into and out of the plane of the work to be manipulated, said manipulator including a rotatable and bodily movable wrench for engaging the work, means for rotating said wrench, and means for changing the axis of rotation of said wrench during its rotary movement, substantially as described. 85

6. In a manipulator, the combination with a feed table of a support, means for moving said support into and out of the plane of the work to be manipulated, said manipulator including a rotatable and bodily movable wrench for engaging the work, means for rotating said wrench, and means for moving the axis of rotation of said wrench in the arc of a circle during its rotary movement, substantially as described. 90

7. In a manipulator, the combination with a feed table of a carriage, means for moving said carriage into different vertical and horizontal planes, a motor mounted on said carriage, a rotatable wrench actuatable by said motor, and means for causing a bodily movement of said wrench in the arc of a circle during its rotary movement, substantially as described. 105

8. In a manipulator, the combination with a feed table of a track, a carriage reciprocal on said track, means for moving said track and carriage, a work manipulating wrench mounted on said carriage, said wrench being mounted for rotary movement, and means connecting said wrench and said carriage and constructed to cause bodily movement of the wrench into different horizontal planes simultaneous with its rotary movement, substantially as described. 110

9. In a manipulator, the combination with a feed table of a carriage, means for causing movement of said carriage, a cylinder 115

- and a piston mounted on the carriage into different vertical and horizontal planes, a frame pivoted to the carriage, a wrench pivoted to the frame, gearing actuated by said 5 piston to cause rotation of the wrench on its axis, and means actuatable by said piston for causing bodily movement of said wrench into different horizontal planes during its rotary movement, substantially as described.
- 10 10. In a manipulator, the combination with a feed table of an oscillating track, a carriage mounted for reciprocation upon said track, fluid pressure means for reciprocating said carriage and oscillating said track and carriage, fluid pressure means 15 mounted on said carriage, a frame mounted for oscillation on said carriage, a work ma- said frame, and means associated with said nipulating wrench rotatably mounted on fluid pressure means for simultaneously ro- 20 tating said wrench and oscillating said frame, substantially as described.

Signed at Lorain, Ohio, this 22 day of February, 1915.

GEORGE C. FARKELL.
